C. E. ROGERS

INSULATOR CLAMP

Filed Sept. 4, 1925

Inventor:
Curtis E. Rogers

By Dodge & Sons,
Attorneys.

UNITED STATES PATENT OFFICE.

CURTIS E. ROGERS, OF LOGAN, WEST VIRGINIA.

INSULATOR CLAMP.

Application filed September 4, 1925. Serial No. 54,540.

To all whom it may concern:

Be it known that I, CURTIS E. ROGERS, a citizen of the United States, residing at Logan, in the county of Logan and State of West Virginia, have invented certain new and useful Improvements in Insulator Clamps, of which the following is a specification.

This invention relates to electrical conductors and particularly to a supporting device for trolley wires.

In some locations, notably in mines having electrical traction, it is necessary to operate at low voltage and in order to avoid undue voltage drops it is necessary to use heavy feeder lines which are connected with the trolley line at short intervals. For many reasons it has been found desirable to arrange the feeder line above and parallel with the trolley line and to support both lines by the same insulator. In this way the construction cost is reduced and the feeder line is brought into closest conducting relation with the trolley line at each common point of support. Structures of this general type have heretofore been devised and used, but so far as I am advised no one of them fully meets the requirements of the service.

Generally stated, these requirements are: The device must be of simple, rugged construction and applicable to existing types of insulator. The feeder clamp must be capable of accepting cables of different sizes without requiring the use of fillers or bushings. It should be possible to unclamp the trolley wire without releasing the feeder and it is desirable to be able to release the feeder without completely dismounting the clamp from the trolley wire. These various requirements are adequately met by my invention, the preferred embodiment of which is illustrated in the accompanying drawings. In the drawings,

Fig. 1 is a fragmentary section of the top of a mine working, showing my device in side elevation attached to a standard type of insulator;

Fig. 2 is a similar view looking from the right relatively to Fig. 1;

Fig. 3 is a perspective view of the elements of the feeder clamp;

Fig. 4 is a sectional view on a slightly enlarged scale on the line 4—4 of Fig. 5;

Fig. 5 is a similar section on the line 5—5 of Fig. 4.

As is usual in the art, the trolley clamp is supported by means of an insulator consisting of a galvanized cast iron shell 11 which sustains a ribbed insulating insert 12. The shell 11 is threaded at 13 to an ordinary expansion bolt indicated generally by the reference numeral 14. This is sustained in the usual manner in a hole drilled for the purpose in the roof of the mine working. The insulating insert 12 sustains fixed thereon a threaded stud 15. The parts so far described are all familiar in the art, being standard articles of commerce.

Threaded on the stud 15 is the upper clamping member of my feeder clamp. This includes a flange-like disc 16 to center a union nut 17 and a lug 18 which serves as one of the cable clamping members. It will be observed that the member 18 is formed with a groove 19 to center the cable and that it projects beyond the disc 16, forming shoulders 20 upon which the nut 17 seats.

The companion clamping member consists of a body 21 of generally cylindrical form, formed with a central slot or channel 22 to receive the feeder cable. The body 21 is threaded at 23 to receive the nut 17. The feeder cable, which is indicated at 24, lies in the slot 22 and is clamped by the lug 18 which is drawn downward into the slot by the nut 17. The nut 17, as stated, is in engagement with the shoulders 20.

The member 21 is formed with a projecting threaded portion of reduced diameter, indicated at 25. On this is threaded a trolley clamp of any suitable form. I have chosen for illustration a commercial clamp shown in the patent to Chandler, No. 1,461,761, but any equivalent clamp might be substituted. This clamp consists of a base member 26 threaded on the portion 25 and carrying two cable clamping jaws 27 which are pivoted to the base 26 by a pin 28. The clamping jaws 27 are urged into clamping relation with a grooved trolley wire 29 by a nut 30 which has a downward projecting flange 31 serving to engage the clamping jaws 27 and swing them toward each other when the nut 30 is screwed downward.

After the insulators have been mounted, the upper cable clamping member 16, 18, with the nut 17 in place, is screwed in place

and lined up properly. The lower clamping member 21, together with the complete trolley clamp, can be shipped assembled and properly aligned with each other, or may be assembled with each other on the job.

The procedure in stringing the cables will be obvious to those skilled in the art and need not be described. I wish to point out, however, that after the two cables are in place it is feasible to release the feeder cable 24 without detaching the clamp from the trolley wire 29, and feasible to release the trolley wire 29 without disturbing feeder cable 24 at all. The possibility of releasing the cable and the trolley wire singly is quite important in maintenance work, and this possibility is a definite improvement over those types of clamp which are so constructed as to release both wires simultaneously.

The construction is compact, there being the least practicable interval between the trolley wire and the feeder cable. No part of the hanger projects in such a way as to be injured by the trolley pole if this runs off. The feeder is electrically connected with the trolley wire at each point of support. Finally, the invention permits the user to avail of any preferred type of trolley wire clamp and any preferred type of insulator, and yet support the feeder cable directly above the trolley wire with the closest practicable spacing, a point of the utmost importance in mine workings.

While the form illustrated and described in detail is the best now known to me, it is obvious that minor variations of form may be made without sacrifice of the advantages characteristic of my invention. Accordingly I do not limit myself to the specific form shown except to the extent specified in the claims.

What is claimed is:

1. A feeder cable support comprising in combination a clamp including a pair of separable cable clamping members and means for clamping said members together

upon a cable; and attaching means at opposite ends of said clamp, one adapted for connection with a support and the other for connection with a trolley wire clamp.

2. A feeder cable support comprising in combination a pair of inter-engaging longitudinally adjustable clamping members adapted to receive a cable between them; means for clamping said members together upon an interposed cable; and attaching means, one on each clamping member, one adapted for connection with a support and the other for connection with a trolley wire clamp.

3. A feeder cable support comprising in combination a clamping member having a transverse cable receiving channel; a clamping member fitting in said channel to clamp a cable therein; a nut swiveled on one of said clamping members and threaded to the other; and attaching means, one on each clamping member.

4. A feeder cable support comprising in combination a clamping member having a transverse cable receiving channel; a clamping member fitting in said channel to clamp a cable therein; a nut swiveled on one of said clamping members and threaded to the other; and substantially axially aligned attaching threads on the respective members for the reception of supporting means and trolley wire clamping means.

5. The combination with a trolley wire clamp and a support therefor of an interposed separable cable clamp serving as a prolongation of said support.

6. The combination with a trolley wire clamp and a support therefor of an interposed cable clamp comprising two inter-engaging clamping members one connected with the support and the other with the trolley wire clamp, and a sleeve nut swiveled on one of said clamping members and in threaded engagement with the other.

In testimony whereof I have signed my name to this specification.

CURTIS E. ROGERS.
